UNITED STATES PATENT OFFICE

2,675,869

GAS MIXER

Mark E. Ward, Columbus, Ohio, assignor to Surface Combustion Corporation, Toledo, Ohio, a corporation of Ohio

Application April 18, 1951, Serial No. 221,643

2 Claims. (Cl. 158—118)

1

This invention relates to gas mixers of the type where a jet of fuel gas from a nozzle is directed into the mouth of a mixing tube in a manner to entrain primary air, mixers of this type being commonly employed with gas burners.

It is well known that air in a dwelling contains lint and that in course of time this lint tends to clog an ordinary air shutter for a gas mixer such as for example a rotary type of air shutter. The object of the present invention is to provide an air shutter of a type that lint in the air cannot readily clog.

For a consideration of what I consider to be novel and my invention, attention is directed to the following specification and the concluding claims thereof.

In the accompanying drawing forming part of this specification—

Fig. 1 is a side elevation with parts in section of apparatus embodying the present invention.

Fig. 2 is a sectional view on line 2—2 of Fig. 1.

Fig. 3 illustrates a modified form of the invention.

Fig. 4 is a sectional view on line 4—4 of Fig. 3.

Fig. 5 illustrates another modified form of the invention.

Fig. 6 is a sectional view on line 6—6 of Fig. 5.

The apparatus with which the present invention has special utility comprises a mixing tube generally indicated at 10, the same being slidably supported in a conduit 11 leading to a burner 12, the conduit being shown as supported on a bracket 13 on a base member 14. The throat of the mixing tube is indicated at 15, the same having a flaring mouth 16. A nozzle for directing a stream of fuel gas into said throat 15 as indicated at 17, the same being mounted in the front end wall 18 of a hollow head or fitting 19 to which gas under pressure is delivered by a supply pipe 20, the head being shown as supported on a bracket 21 mounted on the base member 14.

For reasons presently appearing, the external diameter of the hollow head 19 is such that a substantial portion of its length from the leading face 22 of the end wall 18 is adapted to be telescopically received, like a piston, by the leading end of the throat 15, the range of axial adjustment of said tube 10 being such that it may be backed away from the leading peripheral edge of said face 22 to provide an air gap of substantial size for the admission of a relatively large quantity of air to the mixing tube depending on the kind of fuel being used. On the other hand, where the quantity of air required to be admitted to said throat is so small that the leading periph-

2

eral edge of said face 22 and of said throat would have to be objectionably close together from the standpoint of linting, the present invention, as will presently appear, provides a relatively unrestricted air-inlet port whose effective size may be readily adjusted by varying the distance to which the leading edge of said face 22 extends into said throat 15.

In the form of the invention shown in Fig. 1, the said relatively unrestricted air-inlet port for relatively small quantities of air is generally indicated at 23, the same being formed by a notched or slanting portion 24 on the leading face 22 of said end wall 18 in a direction away from said throat, the slant being shown as beginning at a line or chord below the nozzle 17. It will be readily appreciated that the effective size of said port 23 can be varied as desired by varying the degree to which the leading peripheral edge of said face 22 extends into said throat 15.

In the form of the invention shown in Fig. 3, the leading face of the front end wall 18 of the head 19 is identified by reference numeral 25, the entire surface of said face 25 being in a common plane in contra-distinction to the face 22 in Fig. 1 which has the slanting portion 24. In Fig. 3, the side wall of the front portion of the throat 15 is provided with a triangular or V-shape aperture 26 whose apex is downstream from the leading edge of said throat. When the leading peripheral edge of said face 25 is telescopically received by the leading edge or end of the throat 15, said aperture serves as a relatively unrestricted port for the admission of air to the mixing tube and since the tube is axially adjustable relative to said face 25, the effective size of said port may be varied as desired as will now be readily understood.

In the form of the invention shown in Fig. 5, 40 the air shutter comprises a cylindrical flange 27 on the hollow head 28 to which the gas supply 20 delivers and from the front end of which the nozzle 17 extends, the diameter of said flange being such that it may be telescopically received, 45 like a piston, by the leading end of said throat 15. The leading face 29 of the flange is in a plane which is inclined to the axis of said throat, the entire face of said flange being in said plane. Since the throat 15 is adjustable axially relative 50 to said flange, by varying the degree to which the flange 27 extends within said throat it follows that the effective size of air inlet port between the trailing edge 30 of the face 20 of said flange 29 and the leading end or edge 31 of said 55 throat may be varied as desired.

From the foregoing description, it is believed to be apparent that the present invention provides an air shutter which is well adapted for its intended purpose.

What I claim as new is:

1. In gas mixers formed by a nozzle for discharge of gas into a conduit and an axially movable mixing tube forming part of said conduit and adapted to move toward said nozzle to constitute an air passage between the leading outer edges of said nozzle and tube as the tube moves toward the nozzle, the improvement wherein said leading outer edge of said nozzle is notched to form a wider and relatively unrestricted air passage into the conduit at one point around the periphery of said leading edge as said tube is moved toward said nozzle.
2. In gas mixers formed by members comprising a nozzle for discharge of gas into a conduit and an axially movable mixing tube forming part of said conduit and having a flared mouth, and forming in a closed position a contact area be-

5

tween the nozzle and the tube, a substantial portion of said contact area of one of said members removed to form a wider, relatively unrestricted air passage into the conduit at one portion of 5 said contact area.
